Primary Examiner — Holly E Thurman*Assistant Examiner* — Ieisha N Price(74) *Attorney, Agent, or Firm* — Christensen O'Connor Johnson Kindness PLLC(57) **CLAIM**

The ornamental design for a bracket for a vehicle suspension, as shown and described.

DESCRIPTION

FIG. 1 is a top-front-left perspective view of a bracket for a vehicle suspension according to my new design;

FIG. 2 is a bottom-rear-right perspective view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a rear elevational view thereof; and,

FIG. 8 is a front elevational view thereof.

The dashed broken lines in the drawings show portions of the bracket for a vehicle suspension that form no part of the claimed design.
